UNITED STATES PATENT OFFICE.

MYRON FLEMING, OF ELIZABETH, NEW JERSEY.

DESIGN FOR A MOTOR-BICYCLE FRAME.

SPECIFICATION forming part of Design No. 33,651, dated December 4, 1900.

Application filed May 25, 1900. Serial No. 18,009. Term of patent 7 years.

To all whom it may concern:

Be it known that I, MYRON FLEMING, a citizen of the United States, and a resident of 1017 Magnolia avenue, Elizabeth, in the county of Union and State of New Jersey, have invented 5 a certain new and useful Design for a Motor-Bicycle Frame, of which the following is a specification.

Figure 1 is a side view of the motor-bicycle frame. Fig. 2 is an end view as seen from the right of Fig. 1.

As shown in the drawings, there is a brace A, extending from the position of the axle of the hind wheel of the bicycle. This brace A is forked, both tines of the fork being seen in Fig. 2, but in Fig. 1 the one hides the other. The said brace extends upward and outward, so as to terminate at one end of a motor B. The other end of the motor B is supported 15 upon and against the back tubes C of the frame. The remainder of the frame is old, and therefore needs no description.

By my design I have a well-balanced bicycle and one which is attractive in appearance and ornamental, for the motor is located behind the rider, and any fumes from burning gases or oils, in case it is a gas-engine, are thrown backward, relieving the rider from disagreeable odors. Other advantages are apparent. I have constructed and used such 25 a design, and the motor is not at all in the way of the rider.

I claim as my invention—

The design of a motor-bicycle frame, as herein shown and described. 35

In testimony whereof I have hereunto subscribed my name this 23d day of May, 1900.

MYRON FLEMING. [L. S.]
